LIGHTING FIXTURE

Mitchell Bobrick, Los Angeles, Calif., assignor to Solar Light Manufacturing Co., Melrose Park, Ill., a corporation of Illinois

Filed Jan. 8, 1965, Ser. No. 33,333

Term of patent 14 years

(Cl. D48—31)

FIGURE 1 is a perspective view of a lighting fixture showing my new design, with the standard broken away to indicate indeterminate length;

FIGURE 2 is a top plan view of a light fixture showing my new design;

FIGURE 3 is a fragmentary bottom plan view showing one light housing and part of its support arm;

FIGURE 4 is a side elevational view of FIGURE 3;

FIGURE 5 is a cross sectional view taken on the line 5—5 of FIGURE 1; and

FIGURE 6 is an enlarged perspective view of FIGURE 5.

The dominant features of my design reside in the portions shown in full lines.

I claim:

The ornamental design for a lighting fixture, as shown and described.
